UNITED STATES PATENT OFFICE

120,340

DESIGN FOR AN ELECTRICAL HEATING UNIT FOR COOKING STOVES

Manuel Feldman, New York, N. Y., assignor to
Joseph Gottlieb, Jersey City, N. J.

Application February 14, 1940, Serial No. 90,249

Term of patent 7 years

To all whom it may concern:

Be it known that I, Manuel Feldman, a citizen of the United States and a resident of the city of New York, county of Kings, and State of New York, have invented a new, original, and ornamental Design for an Electrical Heating Unit for Cooking Stoves, of which the following is a specification, reference being had to the accompanying drawing forming part thereof.

Fig. 1 is a top plan view of an electrical heating unit for cooking stoves showing my new design;

Fig. 2 is an edge view of the same; and
Fig. 3 is a bottom plan view of the same.

I claim:

The ornamental design for an electrical heating unit for cooking stoves, as shown.

MANUEL FELDMAN.
